UNITED STATES PATENT OFFICE.

ANDREW MUIRHEAD, OF HAVERHILL, MASSACHUSETTS.

PULP-BEATER.

1,203,240.

Specification of Letters Patent.

Patented Oct. 31, 1916.

Application filed May 7, 1915. Serial No. 26,643.

To all whom it may concern:

Be it known that I, ANDREW MUIRHEAD, a citizen of the United States, residing at Haverhill, in the county of Essex and State 5 of Massachusetts, have invented an Improvement in Pulp-Beaters, of which the following is a specification.

This invention relates to certain improvements in apparatus for performing the 10 pulp-beating operation in the manufacture of paper or box board.

In the operation of the ordinary pulp beater, in which the pulp is circulated horizontally about a midfeather by a beating 15 roll, it is a well-known fact that the nearer any particular portion of the pulp happens to be traveling to the midfeather, the more frequently will it pass beneath the beating-roll, on account of the shorter course which 20 it has to travel in making the circuit, so that if the relative positions of the different portions of the pulp are unchanged, those portions nearest the midfeather will be beaten much faster than the portions next 25 the sides of the tub, and for this reason it is usually necessary for an attendant to stir the contents of the tub frequently, so that the beating action thereon will be more nearly uniform.

30 It is customary to heat the contents of the tub by discharging steam into it closely adjacent one end of the midfeather, and as a result, the pulp is not uniformly heated, the portion nearer the midfeather being heated 35 to a much higher temperature than the portion nearer the sides, and, as it is usually considered preferable to discharge the steam jet downward, the jet has an action to retard the flow of the pulp.

40 In the ordinary operation of a pulp beater, the pulp tends to accumulate at the back fall, and, when the pulp is particularly heavy, or the percentage of water therein is low, so that the circulation in the 45 beater is particularly sluggish, or does not start readily, the pulp frequently overflows the sides of the tub at this point. Moreover the pulp level is, ordinarily, considerably higher adjacent the back fall than elsewhere, 50 so that to prevent the accumulation at the back fall would be to increase the capacity of the tub. While it is a fact that the rapidity of the beating operation increases as the 55 rapidity of circulation increases, and that, within limits, the greater the percentage of

water in the pulp the more rapidly will it be circulated, yet it is also a fact that the greater proportion of material to be beaten to the water, the more the quantity of material which will be beaten for a certain 60 volume of pulp passing beneath the roll. It follows therefore that, under ordinary conditions, the gain which will be secured by reducing the proportion of water is partly lost by the increased slowness with which 65 the pulp will be made to circulate by the beating roll, while the gain made by increasing the proportion of water is partly lost by the decrease in quantity of pulp ground, but, if the speed of circulation may be increased, and at the same time, the proportion of material to the water may be increased, it will be obvious that the rapidity 70 of the beating operation will be increased for both reasons. It is also well known that, 75 in the ordinary operation of a pulp beater, portions of the pulp frequently lodge at different points in the tub and are not moved by the ordinary circulation therein, so that frequent stirring by hand is necessary to 80 dislodge such portions. It is customary, after the pulp has been beaten for a certain length of time, to refine it still further by passing it through a "Jordan" engine. There are numerous objections to this operation, principally on account of the time lost 85 and power required and the danger of cutting the fibers.

The objects of my invention are to improve the operation of the ordinary pulp beater, so that uneven grinding of the pulp is avoided, and the use of hand stirrers is made unnecessary, to increase the production of such pulp beaters, by inducing a more rapid flow of the stuff therein without 90 increasing, but at the same time reducing the proportion of water therein; to cause a more uniform and rapid heating of the pulp in the beater, without retarding, but rather accelerating the flow therein; and to make 95 unnecessary, in many instances, at least, the use of a Jordan engine, so that the beating operation will be finished when the pulp is discharged from the beater, thereby further reducing the time required for the beating 100 operation. I accomplish these objects by providing, in connection with an ordinary pulp-beater, means for withdrawing a portion 105 of the pulp from the tub, preferably at points where it tends to clog or accumulate, 110

that is, adjacent the back fall, and forcibly returning it thereto at such points and in such directions as to cause the flow of the entire contents of the tub to be accelerated, 5 and particularly to cause the flow of the portions thereof more nearly adjacent the sides of the tub, to be accelerated, to a much greater extent than those portions more nearly adjacent the midfeather, so that 10 the proportion of water to the stock may be reduced, thereby increasing the speed of the beating operation and enabling the stock to be beaten with greater uniformity, and without resorting to hand stirring; further 15 by directing a jet of steam into the by-pass pipe through which the pulp is circulated outside the tub, so that the pulp flowing through the by-pass is heated, and its flow therethrough is accelerated, and the entire 20 contents of the tub is heated by the heated pulp discharged therein; further by providing a form of circulating pump in said by-pass, which has a beating action on the pulp, as well as a pumping action, so that it performs 25 the further refining usually performed by the Jordan engine and greatly assists the operation of the beater roll.

For a more complete understanding of my invention reference is made to the accompanying drawing in which;

Figure 1 is a side elevation, and Fig. 2 is a plan view of a pulp-beating apparatus made according to my invention. Fig. 3 is a longitudinal central sectional view of a 35 combined circulating and beating-pump which I preferably employ. Fig. 4 is a cross-sectional view thereof, on the line *a—a* of Fig. 3. Fig. 5 is a detail view of one side of the pump casing. Fig. 6 is a detail sectional view of a peripheral portion of the pump-casing. Fig. 7 is a detail view, showing the coöperative action of the impeller and the peripheral portion of the casing. Fig. 8 is a detail edge elevation of the impeller. Fig. 9 is an enlarged sectional view 45 on the line *b—b* of Fig. 1. Fig. 10 is a longitudinal sectional view on the line *c—c* of Fig. 9. Figs. 11 and 12 are detail sectional views of the inlet nozzles.

50 In the drawing a pulp-beater of ordinary and well-known construction is illustrated, said beater comprising an oblong shaped tub 1, having its side-walls rounded at its ends and provided with a midfeather 2 between which and one side of the tub, the ordinary beater-roll 3 is operated, said roll rotating as usual, between the feed-apron 4, and the back-fall 5.

According to my invention, I connect a 60 circulating pipe 6 to the side of the tub, as closely as practicable to the bottom, and at the middle of the end of the tub next the back-fall, this particular point of connection being desirable though not essential, 65 although I do consider it practically essential

to have this point of connection adjacent the back fall. Said pipe 6 is extended to a centrifugal pump 7, the particular construction of which will be hereinafter more fully described, a right-angular fitting 8 being 70 provided therein adjacent the point where it leads to the central inlet of the pump-casing. The tangential discharge pipe 9, of the pump 7, is connected by a pipe 10, which will be hereinafter more particularly described, to the inlet of a second centrifugal pump 11, of, preferably, identically the same construction as the pump 7, and the tangential discharge pipe 12, from the pump 11, is connected to a gooseneck pipe 13, which 80 is, in turn, connected to a Y-coupling 14, from which branch pipes 14^a, 14^b extend and are connected to fittings 15 and 15^a, respectively. As shown in Figs. 11 and 12, said fittings are bolted to the outer sides of the 85 tub and have nozzles 15^b, 15^c on their inner sides, which project through apertures in the sides of the tub, and have their ends terminating flush with the inner sides thereof, said nozzles being arranged in alinement 90 with the passages through said fittings, to which said pipes 14^a, 14^b are connected. Said fittings are preferably arranged at different elevations and the nozzles at different angles with relation to the sides of the tub, 95 the nozzle of the uppermost fitting 15 being directed at a more acute angle than the lowermost, the angle being such that a jet directed therefrom will be carried, if unobstructed, to points adjacent and beyond 100 the opposite end of the midfeather, while that of the lowermost nozzle is directed at an angle of approximately 45° to the side, so that a jet discharged therefrom will, if unobstructed, strike against the midfeather 105 near its end adjacent the back-fall. While this particular arrangement of nozzles is desirable under some conditions, I do not consider it the most satisfactory under other conditions. That is, different sizes of tubs 110 and different kinds of stock require different arrangements of nozzles. For example, the arrangement indicated in dotted lines in Fig. 2 is desirable under some conditions.

A steam-pipe 16 is connected to the middle 115 of the fitting 8 in a position to direct a jet of steam into the inlet to the pump 7, in alinement therewith, as best shown in Fig. 3. The particular form of circulating pump, indicated in a general way by the characters 120 7 and 11, which I preferably employ, is more particularly shown in detail in Figs. 3 to 8. Said pump comprises a shaft 18, which extends centrally with relation to the side walls 19 and 20, of the pump casing, 125 the wall 19 having a central opening to which the fitting 8 is connected, the shaft extending through a similar opening in the wall 20. A peripheral wall 21 is interposed between the end-walls 19 and 20, the dis- 130

charge-pipe 9 leading tangentially therefrom, as shown in Fig. 4. The impeller 22 is mounted on the shaft 18, to rotate within the casing, and is provided with a series 5 of rearwardly curved blades 22^a, which are in general form, similar to those employed in a well-known form of centrifugal pump. The blades 22^a are of approximately uniform width throughout their entire length, 10 and are of somewhat V-shaped form in cross section, so that each blade is transversely and longitudinally convex on its working side and is provided with two working-faces 22^b, at said side which are 15 arranged at an obtuse angle to each other, said faces meeting in the center line of the impeller and being inclined rearwardly from this point, with relation to the direction of rotation.

20 The end-walls 19 and 20 are provided with a series of radially extending ribs 25, and the peripheral wall 21 with a series of transverse ribs 26, which extend from the ends of said radial ribs. Each of said trans- 25 verse ribs comprises two portions arranged at an angle with relation to each other, said angle corresponding to the angle between the faces 22^b, and meeting in the center of the casing, so that the vertices of the angles 30 between said ribs and between the working-faces of the impeller-blades meet in the same plane. The angles of said faces are ar- ranged oppositely with relation to the angles of said ribs 26, as best shown in Fig. 7. The 35 horizontal portion of the pipe 10 which ex- tends between the two pumps is preferably provided with a series of spirally extending ribs 30 which are formed much after the manner of the rifling of a gun, as best shown in Figs. 9 and 10. A valve 31 is provided in the pipe 6 adjacent the tub, and valves 32 and 33 are provided in the branches 14^a, 14^b to close or regulate the flow there- 40 through.

45 The operation of the apparatus, as a whole, is as follows: The tub is filled and the beating operation is carried on in the ordinary manner, until the larger lumps or bunches of stock are broken up. The valves 50 31, 32 and 33 are then opened and the pumps 7 and 11 are operated, so that the pulp is drawn from the tub through the pipe 6 into the pump 7, which forces it through the rifled-pipe 10, where it is given a whirling action, into the second pump 11, which in turn causes a forcible discharge thereof 55 through the pipe 14, branch pipes 14^a, 14^b, and from the nozzles 15^b, 15^c, back into the tub of the beater. The pulp is thus forced 60 into the tub in the direction of the normal flow of the pulp, but at an oblique angle thereto, the discharge from the upper nozzle 15^b being much more nearly in that direction than that from the other nozzle 65 15^c, as particularly shown in Figs. 11 and 12.

It will be apparent that, as the jets from both nozzles are discharged into a body of water, the force thereof will be dissipated in affecting an acceleration of the flow of the pulp in the tub. It will further be apparent that the accelerating force will be greatest at the end of the nozzle, from which point it will rapidly decrease until it is finally dissipated. As a result the accelerating action on the pulp flowing in the beater 70 will be the greatest on that portion nearest the side-walls, and such action will decrease in force from that point, so that the accelerating force on that portion next the midfeather will be comparatively slight or in- 75 appreciable, according to the force with which the pulp is discharged into the tub. As a result, the flow of the different portions of the pulp is accelerated in proportion to the increased length of the path which such portions have to travel in making the circuit about the midfeather, so that the portions of the pulp nearer the side wall will be caused to make a complete circuit in ap- 80 proximately the same time as the portions 85 nearer the midfeather, with the result that one portion of the pulp will not be beaten substantially more rapidly than another, thereby obviating the necessity of stirring the pulp to prevent uneven beating. 90

With the arrangement of nozzles, above described, the discharge from the one enter- 95 ing the tub at the more acute angle, 15^b is effective approximately to the feed end of the midfeather. The purpose of the other jet 15^c is, particularly, to prevent lodgment 100 of masses of the pulp on the bottom and especially in the angle between the bottom and the midfeather, and by having the dis- charge in a direction more nearly at right 105 angles to the flow, the force of the jet will not be spent before it reaches the mid- feather, so that pulp accumulating against the midfeather will be dislodged. By ad- 110 justing the valves 32 and 33 the relative ef- fect of the jets may be varied according to conditions, or as desired. It will be appar- ent, for example, as indicated in dotted lines 115 in Fig. 2, that differently arranged jets, will have somewhat different effects, in detail, although the general effect will be the same.

By locating the entrance to the by-pass pipe adjacent the back fall, the tendency 120 of the pulp to accumulate to a higher level and to overflow at this point, is prevented, and as the accumulation of pulp at this point is prevented, and the pulp is main- 125 tained at a more nearly uniform level, the excess at the back-fall is removed and delivered at points where the level would otherwise be lower. As the flow of the pulp in the tub is greatly accelerated by the force of the discharge through the by-pass, it be- 130 comes practicable to reduce the proportion of water to the material below that which

is advantageous when the above described arrangement is not employed, so that it is thereby possible both to reduce the time taken to beat a charge properly, and also to increase the amount of material beaten at each charge, most substantially. As the pulp is circulated through the by-pass pipes, as above described, steam is forced into the circulating pulp through the pipe 16, thereby assisting the pumps in circulating the pulp, and at the same time uniformly heating the pulp which passes through said pipe. The pulp thus heated is thoroughly mixed with the pulp in the tub, when returned thereto, so that all portions of the pulp will be heated with substantial uniformity.

An ordinary centrifugal pump, employed in the above relation is effective in breaking up the bunches of stock and performing to a substantial extent, a beating operation, the effectiveness thereof, in this regard, depending, to a considerable extent, on the character of the pulp operated on. However, I preferably construct the pumps 7 and 11, so that they will have a much greater beating action than would an ordinary centrifugal pump. To this end said pumps are provided with said internal ribs 25 and 26, and the impeller blades are constructed to pass in close proximity thereto, but the spaces therebetween are purposely made somewhat greater than the space which would be provided between the impeller and the casing under ordinary circumstances. As the impeller revolves, the stock will be thrown into the spaces between the ribs, and portions thereof will be drawn between the ribs and blades, before it is discharged, so that the same brushing or beating action will take place as in the beater, or as in a Jordan engine. The centrifugal action of the impeller forces a portion of the stock against the peripheral portion of the casing, while, on account of the convex shape of the working faces of the blades, or the arrangement of said faces, so that they slope away from the middle line thereof, with relation to their direction of rotation, there is also a strong tendency to cause the stock to be forced against the side walls of the casing, so that a considerable portion thereof will be drawn between the blade edges and the ribs, and any portions too large to pass between them will be carried through the discharge port. As the stock will pass through two of these pumps before it is returned to the beater, it will be beaten or disintegrated to a considerable extent by the time it is returned to the tub, thus greatly assisting in the beating operation. As the pulp passes through the pipe 10, as it is conducted from one pump to the other, it will be caused to have a whirling or rotary motion, which will also be effective in further disintegrating the stock.

The above described operation is continued until the entire mass of pulp has been reduced to the desired state, and as the refining action of the pumps is substantially the same as that of the Jordan engine, the use of such a machine is rendered unnecessary and the whole operation is performed much more rapidly than when the Jordan engine must be employed, while the time required for the operation in the beater is also greatly reduced, as before stated.

I claim:—

1. A pulp-beater having a circulating passage, and a beating-roll arranged to cause circulation through said passage in a predetermined direction, a by-pass connected to said passage, and means to cause independent circulation through said by-pass, said by-pass being arranged to withdraw the pulp from said passage at one point and return it thereto at another, and having its discharge end arranged to direct a jet in a direction to cause acceleration of the flow in said passage.

2. A pulp beater having a circulating passage and a beating roll to cause circulation through said passage in a predetermined direction, a by-pass connected to said passage at remote points, and means to cause circulation through said by-pass, the discharge end of said by-pass being arranged to discharge a jet therefrom in the direction of and obliquely to said direction of flow in said passage.

3. A pulp beater having a mid-feather and a circulating passage extending about said mid-feather, a beating roll for causing circulation in said passage, a by-pass connected at its ends to said passage, and means to cause circulation through said by-pass, the discharge end thereof being located in the side wall of the tub and arranged to direct a jet across said passage in the direction of and obliquely to the direction of flow therein.

4. A pulp beater having a horizontally disposed circulating passage and a beating roll arranged to circulate the pulp therein, a by-pass leading from said passage at one point and returning thereto at the outer side of the passage at a distance from said point, and arranged to direct a jet obliquely across said passage and in the direction of the flow therein, and means to force the pulp in said passage through said by-pass to accelerate the flow in said passage to a decreasing extent from the outer side thereof inwardly.

5. A pulp beater having a horizontally disposed circulating passage, a mid-feather about which said passage extends, and a beating roll in said passage at one side of said mid-feather to cause circulation therethrough in a predetermined direction, a by-pass leading from said passage and returning thereto at the outer side of the portion

of the passage at the opposite side of the mid-feather from said roll, the discharge end of said by-pass being arranged to direct a jet obliquely to the flow in said passage and in 5 the direction thereof, to accelerate the flow of the pulp in said passage to a decreasing extent from the outer side inwardly.

6. A pulp beater having a circulating passage, a by-pass connected thereto and having means therein to cause circulation therethrough, to withdraw a portion of the pulp from the tub and forcibly return it thereto, a plurality of discharge nozzles connected to the discharge end of said by-pass arranged to cause the pulp to be forced back into the tub at different points, and to accelerate the flow in said passage by the force of such discharge.

7. A pulp beater having a circulating passage and a beating roll arranged to circulate pulp therein, a by-pass connected to said passage at different points, and having means, independent of said roll, to cause circulation therein, the outlet end of said by-pass being branched to provide a plurality of discharge nozzles, said nozzles being arranged to direct jets into said pas-

sage, in the direction of the flow therein, and at different relative angles.

8. A pulp beater having a circulating passage through which the pulp flows in a pre-determined direction, a by-pass connected to said passage at different points, and means to discharge a steam jet into said by-pass in the direction of the flow therein.

9. In combination with a pulp beater having a circulating passage, a by-pass connected to said passage at different points, a rotary pump in said by-pass for causing circulation therethrough, said pump comprising a casing having end and peripheral wall-ports, said end-wall portions having radially extending internally projecting ribs, and an impeller having radially extending blades being arranged to move in co-operative relation with said ribs to perform a combined pumping and beating action.

In testimony whereof, I have signed my name to this specification.

ANDREW MUIRHEAD.
